UNITED STATES PATENT OFFICE.

ELIJAH MCCOY, OF PITTSBURG, KANSAS.

WAGON-TONGUE SUPPORT.

SPECIFICATION forming part of Letters Patent No. 350,937, dated October 19, 1886.

Application filed August 9, 1886. Serial No. 210,459. (No model.)

To all whom it may concern:

Be it known that I, ELIJAH MCCOY, a citizen of the United States, residing at Pittsburg, in the county of Crawford and State of Kansas, have invented a new and useful Improvement 5 in Wagon-Tongue Supports, of which the following is a specification.

My invention relates to an improvement in wagon-tongue supports; and it consists in the 10 peculiar construction and combination of devices, that will be more fully set forth herein-after, and particularly pointed out in the claim.

In the drawings, Figure 1 is a perspective view of a wagon-tongue supporter embodying 15 my improvements. Fig. 2 is an elevation of the same attached to the tongue of a vehicle. Fig. 3 is a top plan view.

The supporter is formed from a single piece 20 of spring metallic rod, which is first bent in the center to form the forward supporting-arm, A. The ends of the spring-rod are then coiled to form the springs B, from which extend the rearwardly-projecting arms C.

D represents a keeper, which is also made 25 of a single rod of metal, and bent substantially in the form of the letter U, thereby forming a yoke or horizontal portion, F, and the vertical arms G. The upper ends of the said arms are bent to form hooks H. These arms G are provided 30 with screw-threads to receive taps I, and the said taps are each provided with a hook, K. As the said taps fit on the threaded arms G, it follows that by rotating the taps the hooks K may be raised or lowered.

35 a represents the front axle of the vehicle. b represents the hounds thereof, and c represents the tongue, which is pivoted on a transverse rod or bolt, d, that connects the hounds near the front end thereof.

40 e represents a transverse rod, which connects the hounds, and is located between the front axle and the pivoted rod or bolt d.

The operation of my invention is as follows: The arm A of the supporter rests under the 45 tongue in advance of the pivotal rod d, and

the arms C have their rear ends extending under the transverse rod e. The keeper D has its yoke F passed through the open coiled springs B of the support, and the arms G of the said keeper extend upwardly on opposite 50 sides of the rear end of the tongue, and are hooked to the rod or bolt d either by means of the hooks H or the hooks K, accordingly as may be required. The front arm, A, of the support has its outer end attached to the under 55 side of the tongue by means of a staple, f.

From the foregoing description it will be readily understood that the weight of the tongue is borne by the support, thus preventing the tongue from bearing down heavily 60 upon the necks of the draft-animals. If it is desired to lower the outer end of the tongue, the hooks H will be caused to engage with the pivotal rod or bolt d, and if it be desired to raise the outer end of the tongue the hooks K 65 will be caused to engage with the said pivotal rod or bolt.

Having thus described my invention, I claim—

The combination of the hounds having the 70 transverse rod e, the tongue, the rod or bolt d, pivoting the tongue to the hounds, the support having the forward-extending arm A, the springs B, and the rearward-extending arms C, the said support having its front end 75 bearing under the tongue and its arm C bearing under the rod e, and the keeper D, having the yoke F attached to the springs, and the vertical arms G, having the hooks engaging with the rod or bolt d, on which the tongue is 80 pivoted, for the purpose set forth, substantially as described.

In testimony that I claim the foregoing as my own I have hereto affixed my signature in presence of two witnesses.

ELIJAH MCCOY.
